US00D659130S

(12) **United States Design Patent**
Chien et al.

(10) **Patent No.:** US D659,130 S
(45) **Date of Patent:** ** May 8, 2012

(54) **WIRELESS MODEM**

(75) Inventors: **Shih-Chieh Chien**, Tu-Cheng (TW);
Po-Ching Huang, Tu-Cheng (TW);
Tzu-Cheng Yu, Santa Clara, CA (US)

(73) Assignee: **Chi Mei Communications Systems, Inc.**, Tu-Cheng, New Taipei (TW)

(**) Term: **14 Years**

(21) Appl. No.: **29/394,678**

(22) Filed: **Jun. 20, 2011**

(51) LOC (9) Cl. **14-03**

(52) U.S. Cl. ..... **D14/242**; D14/138 G

(58) **Field of Classification Search** D14/240,
D14/242, 357, 358, 140-140.2, 140.5, 155,
D14/137, 138 R, 138 G, 138 AD, 348, 349,

(57) **CLAIM**

The ornamental design for a wireless modem, as shown and described.

DESCRIPTION

FIG. 1 is a perspective view of a wireless modem showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines immediately adjacent the shaded areas represent the bounds of the claimed design while all other broken lines are directed to environment and are for illustrative purposes only; the broken lines form no part of the claimed design.

1 Claim, 7 Drawing Sheets
